GOLF BALL

Robert M. Verburg, Plainfield, N. J., assignor to
General Aniline & Film Corporation, New York,
N. Y., a corporation of Delaware

Application October 14, 1948, Serial No. 54,418

3 Claims. (Cl. 273—62)

1
The present invention relates to game balls, more particularly to the provision of a new core therein. It has special reference to the construction of golf balls, although it is also useful in the manufacture of similar game balls such as baseballs.

Golf balls have been made for many years with a semi-hard rubber core about which is wound a tensioned body of rubber thread to build up the ball body which is thereafter encased in an outer covering of rubber.

In recent years liquid cores have come into use, being employed for the construction of the harder golf ball, designed for longer flight and having a highly tensed winding of rubber thread about the core. The liquid core, which customarily is composed of an elastic envelope filled with a suitable liquid, is superior to the semi-hard rubber core for this harder construction, due to its capacity to extensively deform under impact and thereby afford a greater measure of protection to the highly tensed elastic winding. It has the disadvantage, however, of slower recovery after deformation than the semi-solid rubber core with resulting increased lag in restoration of the original center of gravity of the golf ball.

It is the principal object of this invention to provide in game balls, more especially in golf balls, a soft core of simple construction which has the capacity to extensively deform under impact but which has a faster rate of recovery after deformation than the liquid core.

The foregoing and ancillary objects which will become apparent as the description proceeds can be accomplished in accordance with my invention by employing as the material for the core, a highly viscous vinyl alkyl ether polymer which has substantial cold flow at ordinary temperatures.

The aforedefined polymers useful as core material in the game balls of the present invention vary in consistency from balsam-like bodies of lower viscosity to inherently resilient putty-like bodies of higher viscosity and offer accordingly a rather wide choice in selection of material for the core. A recommended general group of the polymers are those having a specific viscosity ranging from about 0.2 to 0.9. Preferred from the standpoint of serving as the core material in golf balls and in other game balls requiring a high degree of resilience, are the polymers having a specific viscosity in the upper range, namely, from about 0.5 to 0.9, which polymers possess inherent resilience. The polymers can be ob-

2
tained by polymerizing in known way, vinyl alkyl ether monomers such as, vinyl methyl ether, vinyl ethyl ether, vinyl isopropyl ether, vinyl n-butyl ether, vinyl isobutyl ether, mixtures of one or more of these monomers with each other and with other polymerizable vinyl compounds where the latter is used in minor amounts which are insufficient to change the character of the polymers from those of highly viscous bodies having substantial cold flow at ordinary temperatures.

The specific viscosity as used herein with reference to the polymers is determined in an Ostwald-Fenske viscometer at 25° C. on a one gram sample of the polymer dissolved in 100 milliliters of benzene.

With the exception of the material forming the core, the game balls of the invention can be made in accordance with the usual practice both as to materials and construction. The core may be fashioned from the polymer in any way found suitable. It can be formed by cold molding the polymer previously chilled to a solid condition. The formed core is maintained in the chilled solid condition for and during the winding operation which is performed with tension on the flexible winding as desired. On subsequent thawing, the original consistency of the core is restored. The outer cover may be applied to the ball body in the usual fashion.

The various features of the invention will be more fully understood by reference to the accompanying drawing which is a partly sectional view of a golf ball embodying the invention.

As shown in the single figure of the drawing, the golf ball is made up of a soft core 1 composed of polymerized vinyl methyl ether of specific viscosity 0.5, which is highly viscous and has substantial cold flow at ordinary temperatures, and a body of rubber thread, tape or other elastic winding 2 wound tightly about the core. The core may be of the same size as the semi-hard rubber core heretofore used. The ball body formed of the core and elastic winding is encased in an outer covering 3, suitably balata, molded thereabout.

While the invention has been described with particular reference to the manufacture of golf balls, it will be readily understood that it is not restricted thereto but may be employed in the manufacture of other game balls, such as, for example, baseballs, wherein yarn rather than rubber thread is wound under tension about the core.

Since various embodiments of the invention

3

herein described may be made without departing from the spirit or scope thereof, it is not intended that the invention be limited except as is required by the prior art and the appended claims.

The term "specific viscosity" as used herein is taken from Bawn "Chemistry of High Polymers" at page 162, wherein it is stated:

"The increase in viscosity η of a polymer solution over that of the pure solvent η_0 is expressed as a fraction, called the specific viscosity η_{sp} according to

$$sp = \frac{\eta - \eta_0}{\eta_0} = \eta_r - 1$$

where η_r is termed the relative viscosity and is equal to

$$\frac{\eta}{\eta_0}$$

The specific viscosity is dependent on the concentration, and in order to define a quantity characteristic of a given macromolecule in a solvent it is necessary to take the initial slope of the η_{sp} versus concentration curve, i. e.

$$\lim_{C \rightarrow 0} \frac{\ln \eta_r}{C} = c \rightarrow 0 \quad \frac{\ln \eta_r}{C} = [\eta]$$

I claim:

1. A golf ball having a soft core consisting of a

polymerized vinyl alkyl ether of specific viscosity from about 0.5 to 0.9 and a body of elastic thread wound tightly about the core.

2. A golf ball having a soft core consisting of polymerized vinyl methyl ether of specific viscosity from about 0.5 to 0.9 and a body of elastic thread wound tightly about the core.

3. A golf ball having a soft core consisting of a polymerized vinyl alkyl ether of specific viscosity from about 0.2 to 0.9 and a body of elastic thread wound tightly about the core.

ROBERT M. VERBURG.
